CAR UNDERFRAME

Jerome G. Bower, New York, N. Y., assignor to
The Buckeye Steel Castings Company, Colum-
bus, Ohio

Application December 24, 1931, Serial No. 583,111

4 Claims. (Cl. 105—415)

This invention relates to improvements in car underframes and more particularly to a car underframe formed of a single piece metal casting. More specifically, the invention pertains to underframes for mine cars, but it is not restricted to this use, as such underframes can be used on many other types of cars.

Heretofore it has been customary to build cars by using an underframe which has transverse and longitudinal beams for carrying the load and distributing the same to the car axles, and which has a floor plate secured to its top. Side plates are riveted to the sides of the underframe to complete the car body. As the above mentioned underframe beams must be of an appreciable depth below the floor plate, the space between the bottom of the beams and the top of the floor is not utilized, and this results in a waste of space. Furthermore, some types of underframes require the assembly of many parts, causing a high labor cost. It is customary in the known constructions to use rolled steel plates for the floor, and these corrode easily and have to be replaced, which results also in high maintenance cost.

An object of this invention is to provide in a one-piece metal casting, all the essential features of a car underframe, including the car floor and pedestals for the axle journal boxes.

Another object is to provide a one-piece metal underframe of pan form and including a corrugated floor plate and means to facilitate the attachment of side plates to the frame.

A further object is to furnish an underframe which will increase the cubical contents of the car body without increasing the weight or cost.

Another object is to provide an underframe on which a car body of specified cubical content may be built at less expense of material and weight.

A still further object is to furnish a one-piece car underframe including a corrugated floor plate, draft gear pocket and journal box pedestals. The corrugated shape of the floor will remove the necessity for cross beams and make the car floor self supporting.

With the foregoing objects outlined and with other objects in view which will appear as the description proceeds, the invention consists in the novel features hereinafter described in detail, illustrated in the accompanying drawings, and more particularly pointed out in the appended claims.

In the drawings.

Fig. 1 is a top plan view of one-half of a car underframe made in accordance with my invention.

Fig. 2 is an end view of the same partially in transverse vertical section.

Fig. 3 is a side elevation of the same.

Figs. 4, 5 and 6 are vertical sectional views taken respectively on the lines 4—4, 5—5 and 6—6 of Fig. 1.

Fig. 7 is a top plan view of one-half of a modified form of underframe.

Fig. 8 is an end view partly in transverse vertical section of the modified form.

Figs. 9 and 10 are sectional views of the modification taken respectively on the lines 9—9 and 10—10 of Fig. 7.

Fig. 11 is a view similar to Fig. 8, but showing a further modification.

Fig. 12 is a sectional view of a detail of this further modification, taken on the line 12—12 of Fig. 11.

Referring to the embodiment of the invention illustrated in Figs. 1 to 6 inclusive, 10 designates a car underframe formed of a one-piece metal casting of substantially pan formation. I prefer to make such underframe out of cast steel since this material is known to resist corrosion to a greater extent than rolled shapes, and the metal can be distributed to better advantage in providing for strength and against corrosion. Such underframe will be supported by the usual car wheels 11. The plate which forms the bottom or floor of the car is of corrugated form, and such corrugated shape greatly increases the load carrying capacity of the car floor and allows the floor to be located below the top of the underframe casting, so that space heretofore wasted can now be utilized. End flanges 13 and side flanges 14 which form an endless wall upstanding from the floor, add strength to the underframe and provide means for securing the side sheets (not shown) of the car body to the underframe. It will be observed that such flanges are provided with rivet holes. Integrally united with the medial longitudinal portion of the underframe are the coupler pocket 15 and coupler carrier 16, the draft gear pockets 17, and the draft stops 18. Pedestal jaws 19 depend from the opposite sides of the underframe and each is associated with a spring seat 20 and a spring retaining lug 21. Lugs 22, 23 and 24 for the attachment of brake parts (not shown), also depend from the floor, and of course, all of the parts 19, 20, 21, 22, 23 and 24 are integral parts of the casting.

Longitudinal ribs 26 serve to reinforce the rear draft stop 18 and merge into the car bottom; and transverse ribs 27 reinforce the draft gear and

coupler pockets and are also integral with the floor.

A rapping block 25 may be secured to the underside of the car and occupy the inverted channel which extends longitudinally of the medial portion of the floor, in case the car is of the dump type, and it is desirable to loosen the contents by rapping.

The embodiment disclosed in Figs. 7 to 10 inclusive differs principally from that shown in Figs. 1 to 6, in that the specific shape of the floor has more rounded surfaces, as shown at 12a, and the central inverted groove which receives the rapping block 25a has a thickened wall 15 as shown at 25b.

In Figs. 11 and 12, the bottom is of undulated shape, as indicated at 12b, and there are a greater number of ridges and valleys than in the embodiments shown in the other figures. 20 Furthermore, each end flange 13a in this embodiment forms an apron 13b which projects downwardly below the floor plate.

The novelty of such embodiments lies principally in the corrugated contour of the car floor or bottom 12, and in the fact that the floor is positioned below the top of the underframe proper. While the drawings show the corrugations running longitudinally of the underframe, it is to be understood that they can run 25 transversely or diagonally of the underframe if desired. In either event, such formation will add capacity to the car body and strengthen the underframe. However, I prefer to have the corrugations run longitudinally for in that position they add column strength to the car for 30 resisting draft forces. I believe it is also novel to make the coupler pocket, coupler carrier, draft gear pocket, pedestal jaws, etc., integral parts of a casting having a corrugated floor positioned 35 below the top of the underframe.

40 From the foregoing it is believed that the construction, use and advantages of the invention may be readily understood, and I am aware that changes may be made in the details disclosed, without departing from the spirit of the invention, as expressed in the claims.

What is claimed and desired to be secured by Letters Patent is:

1. In a mine car or the like, a car underframe 50 formed of a one-piece metal casting of substantially pan-shape and having a corrugated bottom forming a car body floor, said corrugations extending lengthwise substantially the full length of the underframe, one of said corrugations forming a central groove at the bottom of the underframe at the center thereof, a coupler carrier arranged beneath the central portion of the underframe where said groove is located, other corrugations of the bottom forming side grooves 55 at opposite sides of the central groove, said underframe having an upstanding perimeter wall projecting from said floor and integral with the floor, and supporting wheels for the car, projecting into the side grooves.

2. In a mine car or the like, a car underframe 5 formed of a one-piece metal casting of substantially pan-shape and having a corrugated bottom forming a car body floor, said corrugations extending lengthwise substantially the full length of the underframe, one of said corrugations forming a central groove at the bottom of the underframe at the center thereof, a coupler carrier arranged beneath the central portion of the underframe where said groove is located, other corrugations of the bottom forming side grooves at opposite sides of the central groove, said underframe having an upstanding perimeter wall projecting from said floor and integral with the floor, supporting wheels for 10 the car, projecting into the side grooves, and pedestal jaws depending from the opposite side portions of the underframe and positioned outwardly of said wheels.

3. In a mine car or the like, a car underframe 20 formed of a one-piece metal casting of substantially pan-shape and having a corrugated bottom forming a car body floor, said corrugations extending lengthwise substantially the full length of the underframe, one of said corrugations forming a central groove at the bottom of the underframe at the center thereof, a coupler carrier arranged beneath the central portion of the underframe where said groove is located, other corrugations of the bottom forming side 25 grooves at opposite sides of the central groove, said underframe having an upstanding perimeter wall projecting from said floor and integral with the floor, supporting wheels for the car, projecting into the side grooves, and pedestal jaws 30 depending from the opposite side portions of the underframe and positioned outwardly of said wheels, said floor having longitudinal grooves in its top surface arranged immediately above said pedestal jaws.

4. In a mine car or the like, a car underframe, 40 formed of a one-piece metal casting of substantially pan-shape and having a corrugated bottom forming a car body floor, said corrugations extending lengthwise substantially the full length of the underframe, one of said corrugations forming a central groove at the bottom of the underframe at the center thereof, an integral coupler carrier arranged beneath the central portion of the underframe where said groove is 45 located, other corrugations of the body forming side grooves at opposite sides of the coupler carrier to accommodate wheels of the car, pedestal jaws integral with the floor and depending from the floor outwardly of said side grooves 50 to accommodate the axle of said wheels, said underframe having an upstanding perimeter wall projecting from said floor and integral with the latter, opposite side portions of said wall being positioned immediately above the outer portion 55 of the pedestal jaws.

JEROME G. BOWER.
